UNITED STATES PATENT OFFICE.

PIERRE BOSSU, OF PARIS, FRANCE, ASSIGNOR TO SOCIÉTÉ ANONYME DES ÉTABLISSEMENTS L. BLERIOT, OF PARIS, FRANCE.

ELECTROMAGNET.

1,242,763.

Specification of Letters Patent.

Patented Oct. 9, 1917.

Original application filed December 14, 1912, Serial No. 736,838. Divided and this application filed December 19, 1913. Serial No. 807,772.

To all whom it may concern:

Be it known that I, PIERRE BOSSU, a citizen of the Republic of France, residing at Paris, France, have invented certain new 5 and useful Improvements in Electromagnets, of which the following is a specification.

The present invention relates to improvements in electro-magnets and similar devices 10 having an armature movable relatively thereto, and the object of this invention is to provide means to compensate for the effects of the variations in reluctance occurring in the magnetic field due to the varying 15 distances of the armature from the core of the magnet, a resistance being used, according to the present invention, which is adapted to be connected in series with the winding of the electro-magnet and the value 20 of which is so modified as to compensate for the variations in reluctance in every position of the armature, or practically so. The present application is a division of my prior application, Serial No. 736,838, filed December 25, 1912.

To these and other ends, the invention consists in certain improvements, and combinations and arrangements of parts, all as will be hereinafter more fully described, the 30 novel features being pointed out particularly in the claims at the end of the specification.

In the accompanying drawing:—

Figure 1 is a view in elevation showing 35 an electro-magnet having the present invention applied thereto;

Fig. 2 is a side elevation of an electro-magnet equipped with another embodiment of the invention;

Fig. 3 shows an end elevation of the same. Similar parts are designated by the same reference characters in the several views.

In each instance shown the electro-magnet embodies a core *a*, the core illustrated in 45 Figs. 1 and 2 being of horse-shoe form and the cores are provided with windings or coils *b* to excite them. *c* represents in each instance the armature which is movable toward and from the magnet core. As shown in Fig. 1, the armature *c* is pivoted at one end on the axis *c'*, and the opposite or movable end of the armature is connected by a link *c*² to a lever or arm *m*, the latter being pivoted at *m*^o whereby the opposite end of

this lever or arm will swing in an arc. This 55 free or movable end of the lever or arm *m* is provided with a brush *m'*. One side of the circuit is connected to one terminal of the coil or winding *b* while the other side of the circuit is connected to the swinging lever 60 or arm *m* preferably at the pivot *m*^o. A resistance is provided which is adapted to be connected in series with the coil or winding of the electro-magnet. The resistance *d* shown in Fig. 1 has a contact portion of arc- 65 like or segmental form, and the brush *m'* maintains engagement with this segmental portion of the resistance while the armature occupies a position in contact with the core, the released position shown in Fig. 1, and 70 also any intermediate positions. This resistance *d* is so calculated that it will compensate for the effects of the variations in reluctance of the magnetic field for all positions of the armature, the value of the resistance being at a minimum or practically zero 75 when the armature is in fully released position, and the value of the resistance will increase progressively as the armature moves toward contact position, it having a maximum value when the armature reaches contact position. As the armature moves from contact position to released position, the value of the resistance will decrease proportionately until it reaches a minimum or 80 zero value when the armature is in fully released position.

In that embodiment of the invention shown in Figs. 2 and 3, the armature *c* is pivoted on an axis *c'* as before, the armature, however, being shown above the magnet instead of below as in the preceding instance and consequently means is provided for returning the armature to released position when the core of the magnet is de- 90 energized or its magnetism or attractive force falls below a given value, it having a lever *o* which is mounted at an intermediate point on a pivot *o*^o and is connected at one end to the free end of the armature 100 *c* by the link *o*² and has a spring *o*⁴ acting upon its opposite end with a force tending to lift the armature and thereby move it toward or into released position. An arm *o*' is fixed to the lever *o* and is acted on by an 105 expansion spring *o*³.

In this embodiment of the invention, the resistance comprises a plurality of coils *d*',

- d*², *d*³ and *d*⁴, the terminals of these coils or resistance sections being connected to contacts *e*', *e*², *e*³ and *e*⁴, the remaining terminal of the coil or resistance section *d*⁴ being connected to a contact *e*⁵ which latter in turn is connected directly to one side of the circuit. The armature *c* carries or is operatively connected to a switch which is adapted to control the resistance contacts.
- 10 This switch in the present instance embodies a series of switch blades *n*', *n*², *n*³, *n*⁴ and *n*⁵ which are of varying curvatures. These switch blades are all connected in common at their attached ends to the winding of
- 15 the electro-magnet, the latter being connected to the opposite side of the circuit. When the armature is in contact position as shown in Figs. 2 and 3, the switch blades are all out of contact with the resistance contacts, except the switch blade *n*' of greatest curvature which is then in engagement with the contact *e*' of the resistance and hence the resistance at this time will have the highest value as the exciting current for
- 20 the magnet must flow through all the coils of the resistance. As the armature moves in a direction from the contact position and toward released position, the switch blades *n*², *n*³, *n*⁴ and *n*⁵ of diminishing curvatures
- 25 will successively engage the resistance contacts *e*², *e*³, *e*⁴ and *e*⁵, thereby cutting out of the circuit the resistance coils *d*', *d*², *d*³ and *d*⁴ and diminishing the value of the resistance until the armature is in fully released position at which time the contacts *n*'

and *e*⁵ will be in engagement and the resistance will be of zero value. As the armature moves from its released to its attracted or contact position, the coils of the resistance are successively inserted in the magnet circuit by a reverse operation of the switch and thereby the value of the resistance is progressively increased until it reaches a maximum when the armature is in contact or attracted position.

As shown in the drawings a sheet of non magnetic material *f* is preferably interposed between the core *a* and the armature *c*.

I claim as my invention:—

The combination with an electro-magnet 50 and a relatively movable armature, of resistance divided into a series of coils having individual contacts, and a switch movable by the armature and embodying a series of 55 spring blades of different curvatures arranged to coöperate with respective contacts of the resistance coils whereby the resistance is progressively increased when the armature moves toward contact position and is diminished as the armature moves toward 60 released position to compensate for the effects of variation of reluctance of the magnetic field for all positions of the armature.

In testimony whereof I have hereunto set 65 my hand in presence of two subscribing witnesses.

PIERRE BOSSU.
